EXHAUST STEAM PRESSURE CONTROL FOR INJECTORS

Filed March 23, 1925

Patented Aug. 7, 1928.

1,680,075

UNITED STATES PATENT OFFICE.

ROY J. VAN METER, OF STURGIS, MICHIGAN, ASSIGNOR TO THE SUPERHEATER COMPANY, OF NEW YORK, N. Y.

EXHAUST-STEAM-PRESSURE CONTROL FOR INJECTORS.

Application filed March 23, 1925. Serial No. 17,496.

My invention relates to exhaust steam injectors, and particularly to the type employed for supplying feed water to locomotive boilers, typical forms of which are exemplified in United States Letters Patent No. 1,342,128, issued to J. J. C. and R. D. Metcalfe on the 1st day of June, 1920, and No. 1,442,532, issued to R. D. Metcalfe, et al., on the 16th day of January, 1923.

In injectors of this general type the motive fluid for normal operation is exhaust steam supplied from the locomotive engine, which may or may not be supplemented by live steam from the boiler. During periods when the engine is not running the injector is operated, if necessary, by auxiliary live steam supplied directly from the boiler.

The characteristics of the exhaust steam injector are such that variations in the proportion of water and exhaust steam supplied thereto must be kept within reasonable limits and for this reason a close regulation of these elements is highly desirable. The regulation of the water supplied to the injector is comparatively simple, as any variations in the pressure under which the water is supplied are slow and gradual, but the regulation of the exhaust steam supply is a more difficult problem. Because of the wide variations in the conditions under which the locomotive engine operates there is a very considerable variation in the exhaust steam pressure, and, as will be easily understood, in the ordinary operation of the locomotive it is not always possible to have available exhaust steam at high pressure. The injector is therefore designed to work satisfactorily with moderate exhaust steam pressures, that is, pressures extending through a range of from about 10 inches of vacuum to 20 pounds per square inch pressure. Variations in the exhaust steam pressure in this range can be satisfactorily taken care of by proper regulation of the injector. Under some conditions, however, for instance when the locomotive is working under heavy loads and the engine is operating with fully open throttle and maximum cutoff, the exhaust pressure will rise above that at which the injector will operate satisfactorily. Under conditions such as these the injector becomes abnormally sensitive and is likely to "break" and cease operating, that is, due to the improper proportioning of the steam and water entering the injector the water velocity is

lost, the boiler check closes and the steam and water mixture is discharged through the injector overflow.

It is the object of my invention to eliminate the possibility of the injector "breaking" because of excessive pressure of the exhaust steam supplied thereto, by automatically limiting the pressure which can be maintained in the exhaust steam supply line, and it is a further object to accomplish this by means which may be cheaply and readily applied to existing installations and which will have no undesirable effect upon the back pressure against which the engine must work. Other and further objects will appear as the description proceeds.

In the accompanying drawings I have shown two forms of apparatus suitable for carrying out my invention, Figure 1 being a diagrammatic fragmentary elevation partly in section of a locomotive equipped with an exhaust steam injector to which my invention has been applied, and Figure 2 being a vertical section through the exhaust pipe and a portion of the cylinder saddle of a locomotive showing another form of apparatus which may be employed in the exercise of my invention.

Referring now to Figure 1, the locomotive is indicated generally at 1, and has applied thereto the exhaust steam injector 2, having a water inlet 3, and discharging to the locomotive boiler through the feed pipe 4 and check valve 4'. Exhaust steam for the normal operation of the apparatus is supplied through conduit 5, which is connected into the exhaust passage 6 of the cylinder saddle 7. Live steam is supplied to the injector through the supplementary steam pipe 8 and the auxiliary steam pipe 9 and the regulation of the device is accomplished through the water valve 10 and nozzle control 11. These various controls need not be described in detail, as the specific form of the exhaust steam injector forms no part of the present invention.

As has heretofore been mentioned, under certain working conditions the exhaust steam pressure in the passage 6 rises to an undesirably high degree, and in order to prevent this high pressure from affecting the operation of the injector I provide a relief valve at the injector end of the supply pipe 5, designed to limit the pressure at which exhaust steam may be supplied to the in-

jector. For this purpose any suitable form of relief valve may be employed and I have shown a conventional form comprising a main valve body 12 adapted to receive a valve seat 13, upon which there is suitably mounted a bonnet 14 carrying the valve 15, which is maintained on a seat by the spring 16 carried within the bonnet.

The maximum pressure which may be maintained in the supply pipe 5 is determined by the tension of the spring 16 and if this pressure is exceeded the valve 15 will lift and relieve the excess pressure by allowing a portion of the steam to escape through the outlet pipe 17. It is to be understood that any type of valve suitable for this purpose comes within the scope of my invention and that the regulation of the pressure may be accomplished by any well known means, as for instance the substitution of springs of different strength or the provision of means for regulating the tension on the spring employed.

In order to utilize to the fullest extent the steam which is delivered into the outlet pipe 17 and also to eliminate what might otherwise be an objectionable exhaust I prefer to place the discharge end of the pipe 17 under the extension of the locomotive stack 18 so that steam leaving the pipe 17 will be exhausted up the stack together with the steam issuing from the exhaust pipe 19, and form a draft creating means supplementing the action of the main exhaust. It is to be understood, however, that this particular disposition of the excess steam is not an essential factor in the exercise of my invention.

In the modified form as illustrated in Figure 2, exhaust steam is supplied to the injector from the exhaust passage 6' through the supply pipe 5' which leads directly to the injector, and excessive steam pressure is prevented from reaching the injector by means which limit the maximum pressure which may be maintained in the exhaust passages 6'. In the form shown this means comprises a main exhaust pipe 19' having a nozzle outlet 20 through which all of the steam exhausted up the stack normally passes. An auxiliary passage 21 is provided in the pipe 19' leading to a supplemental steam outlet 22, the passage 21 being normally closed by a pressure relief valve of suitable type which in the present case has been shown as a duplicate of that already described in connection with Figure 1. In

general the operation of this form of the apparatus is similar to that already described, with the relief valve normally in closed position and opening when the pressure in the exhaust passage exceeds a certain pre-determined figure. It will be obvious that upon the opening of the valve any excess pressure will be relieved through the additional area of outlet opening which is brought into play.

While in the form shown in both Figures 1 and 2 the secondary or auxiliary steam outlet is shown as a port at one side of the main exhaust nozzle, it is to be understood that any suitable form of opening such as an annulus around the main nozzle, or a centrally located jet may be employed without departing from the scope of the invention.

I claim:

1. The combination of a boiler, an injector supplying feed water thereto, means for supplying exhaust steam to said injector, and a pressure relief valve located in said means, said valve being normally closed and opening only when the pressure within said means exceeds a pre-determined figure.

2. The combination of a boiler, an injector supplying feed water thereto, a flue gas outlet, an exhaust passage delivering draft creating steam through said outlet, a connection from said pipe carrying exhaust steam to said injector, a pressure relief valve for maintaining the pressure of the steam supplied to said injector below a pre-determined figure, and means discharging steam passing through said valve through said outlet.

3. The combination of a boiler, an injector supplying feed water thereto, an inlet pipe supplying exhaust steam to said injector, and a relief valve located in said inlet pipe and limiting the pressure maintainable in said pipe to a pre-determined figure.

4. The combination of a boiler, an injector supplying feed water thereto, a flue gas outlet, an exhaust passage delivering draft creating steam through said outlet, a connection from said passage supplying exhaust steam to said injector, a pressure relief valve in said connection adapted to open only when the pressure within said pipe exceeds a pre-determined figure, and a pipe connected to the outlet of said valve and discharging steam passing therethrough through said outlet.

ROY J. VAN METER.
